[57] CLAIM

The ornamental design for a book-shaped case having an inner recess to house a medal, as shown and described.

DESCRIPTION

FIG. 1 is a front elevational view of a book-shaped case having an inner recess to house a medal, showing my new design;

FIG. 2 is a left side elevational view thereof;

FIG. 3 is a rear elevational view thereof;

FIG. 4 is a right side elevational view thereof;

FIG. 5 is a top plan view thereof;

FIG. 6 is a bottom plan view thereof;

FIG. 7 is a perspective view thereof; and,

FIG. 8 is a perspective view thereof, having the cover in an open position.
